US0D1059377S

(12) **United States Design Patent** (10) Patent No.: **US D1,059,377 S**
(45) Date of Patent: ** Jan. 28, 2025

(54) **DISPLAY SCREEN WITH GRAPHICAL USER INTERFACE**

(71) Applicant: **Microsoft Corporation**, Redmond, WA (US)

(72) Inventors: **Diego D. Baca Del Rosario**, Seattle, WA (US); **Tyler White**, Seattle, WA (US); **Ryan C. Pendlay**, Redmond, WA (US); **Peter Hammerquist**, Shoreline, WA (US); **Spencer I. Hurd**, Seattle, WA (US); **Jeremy S. Knudsen**, Monroe, WA (US)

(73) Assignee: **Microsoft Corporation**, Redmond, WA (US)

(**) Term: **15 Years**

(21) Appl. No.: **29/842,600**

(22) Filed: **Jun. 14, 2022**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen with graphical user interface as shown and described.

DESCRIPTION

FIG. 1 is a front view of a first embodiment of a display screen with graphical user interface showing our new design; and,

FIG. 2 is a front view of a second embodiment of a display screen with graphical user interface showing our new design.

The exterior even-length broken lines illustrate the boundary of the claimed design and portions of a display screen and form no part of the claimed design. The remaining even-length broken lines illustrate portions of the graphical user interface and form no part of the claimed design. The broken line text forms no part of the claimed design.

1 Claim, 2 Drawing Sheets
